UNITED STATES PATENT OFFICE

2,585,879

CIRCUIT BREAKER

Anthony Van Ryan, South Milwaukee, Wis., assignor to McGraw Electric Company, a corporation of Delaware

Application January 26, 1949, Serial No. 72,916

2 Claims. (Cl. 200—144)

1

This invention relates to circuit breakers which may be of the repeating or single shot type. For instance, the circuit breaker may be generally of the type shown and described in the copending application of Anthony Van Ryan and Carl Schindler, Serial No. 585,238, filed March 28, 1945, for Circuit Interrupter, now Patent Number 2,560,831, dated July 17, 1951, and owned by the same assignee as the present invention.

Circuit breakers frequently have to handle heavy currents which produce a violent arc and this arc tends to "hang on" or persist with consequent damage to the contacts. It has been found that the arc tends to enlarge the cross-sectional area of the gaseous conducting path and that it becomes increasingly difficult to extinguish the arc as the expansion of the arc, or gaseous conducting path increases. When attempts have been made to limit the expansion of the arc by the use of arc chutes or chambers, it frequently resulted in the shattering or breaking of the arc chutes or constricting chambers, such result being particularly noticeable where the arc chutes were made of porcelain or similar rigid material.

This invention is designed to overcome the above noted defects and objects of this invention are to provide a circuit breaker which will quickly suppress or interrupt the arc, which will prevent rapid wear or damage of the contacts, which will prevent the building up of dangerous gas pressures, and which will control not only the volume or cross-sectional area of the arc, but also its direction to thereby prevent the arc from striking or reaching metal parts of the circuit breaker other than the contacts.

In greater detail, further objects of this invention are to provide a circuit breaker which has the stationary contacts located in substantially enclosing pockets whose walls are formed of insulating material and which are provided with gas vents to allow the quick discharge of gas and the quick refilling of the pockets with oil after a circuit interruption, which has a constricted slot-like space through which the operating arm carrying the movable contacts on each side of the circuit breaker passes which, therefore, has a constricted slot-like space into which the arc would have to pass as it moved inwardly in an attempt to reach or strike other metal portions of the circuit breaker than the contacts, and to so form this slot-like portion that it is arcuate and widens or opens outwardly towards the front and bottom, and to provide extensive, cold, insulating surfaces over which the arc

would be forced to pass as it moved inwardly, the construction being such as a preclude the undue expansion of the arc or gaseous conducting path and to cool the arc and control its direction.

A further important feature of this invention is to provide a construction whereby the insulating walls of the chambers for the two movable contacts and the stationary contacts are flexible and will yield slightly under heavy gas pressure, thereby cushioning any shock stresses and preventing damage to the circuit breaker.

An embodiment of the invention is shown in the accompanying drawings, in which:

15 Figure 1 is a view of the lower portion of the circuit breaker with parts broken away and parts in section showing the circuit breaker in closed position.

20 Figure 2 is a view somewhat similar to Figure 1 showing the circuit breaker in open position.

Figure 3 is a rear view of the lower portion of the circuit breaker showing the circuit breaker in closed position.

25 Figure 4 is a line section on the line 4—4 of Figure 1, such section being through one side only of the circuit breaker.

Figure 5 is a fragmentary section on the line 5—5 of Figure 1.

30 Figure 6 is a view of the movable contact assembly detached from the remainder of the circuit breaker.

Referring to the drawings it will be seen that the circuit breaker includes a current responsive operating member indicated by the reference character 1. This operating member is in the form of a plunger and is actuated as described in the above noted copending application. Suffice it to say, however, that the operating member 1 is responsive to overload conditions and is forced downwardly on the occurrence of an overload. This operating member depresses a roller 2 carried by a lever 3 which may, in reality, consist of a pair of insulating links or arms. This lever is connected by means of an insulating link 35 4 with a guiding lever 5 pivoted as indicated at 6. In reality, the lever 5 consists of a pair of insulating members. It carries a transversely extending pin 6' at its outer end to which the outer ends of a pair of tension springs 7 are attached.

40 45 50 The other end of the tension springs 7 are looped over an insulating sleeve 8 through which a metallic rod or cross bar 9 extends. This rod or cross bar 9 is attached at its outer ends to a pair of insulating members or switch arms 10. 55 These switch arms 10 are pivoted as indicated

at 11 at their inner ends and at their outer ends resiliently support the movable contacts 12.

The circuit breaker has a main U-shaped, insulating body portion 13 which has downwardly extending spaced walls 14 as shown most clearly in Figure 3 and these spaced walls are slotted as indicated at 15 in Figure 1 to provide room for the free travel of the cross-bar 9 with its insulating sleeve 8.

The stationary contacts are indicated by the reference character 16 and are resiliently supported as shown.

The general mechanism, as described thus far, is substantially the same as that set forth in the above noted copending application and in itself and standing alone forms no part of this invention. This invention is primarily directed to the construction of a circuit breaker which enables the arc to be confined to a limited space and which directs and suppresses the arc and prevents the arc from striking in an undesirable manner to metal portions of the circuit breaker. To accomplish these results, the arc is confined to a relatively narrow slot-like portion which widens towards the outer side of the circuit breaker and narrows towards the inner side thereof. This is accomplished by providing outer insulating plates 17 on opposite sides of the circuit breaker and spaced from the main side walls 14. Within this space the movable and stationary contacts 12 and 16 are located. In addition to this, arcuate, insulating members 18 are attached to the inner walls or plates 21 and if desired a skirt-like extension 19 may be provided as shown in Figures 1 and 2.

The insulating members 18 project outwardly towards the outer insulating plates 17 and they may be formed of fiber together with the outer plates 17, so that as the arc transverses the cold fiber surfaces, a deionizing gas is evolved which further assists in the extinguishing or suppressing of the arc in a well known manner. However, it is to be noted particularly that the space, as shown for instance in Figure 4, or the slot between the outer insulating walls 17 and the insulating barrier members 18 is relatively restricted. It is to be noted particularly that the construction is such that a very narrow slot is provided between the members 18 and their corresponding outer walls 17 and that a relatively larger, though still constricting slot-like space is left between the skirt portions 19 of the members 18 and the outer walls 17. The switch arms extend through the narrow slots and the movable and stationary contacts are located in the larger, though still narrow slot-like portions hereinabove described. Further than this, it will be seen that the construction is such that the spacing, insulating members 20 provide substantial pockets for the stationary contacts 16. Preferably, gas vent holes 21 are provided through the outer walls 17 which communicate with the pockets for the stationary contacts to prevent trapping of gas in these pockets.

The mode of the operation is apparent from the above description and it will be seen that when the pin 6' is rocked past dead center with reference to the pivot 11 of the switch arms 10 that the movable contacts will snap downwardly and will produce a quick break. Under heavy overloads the arc will tend to persist but it will have to traverse extended and cold insulating surfaces or faces, namely the opposed surfaces of the insulating members 18 and 19 and the outer insulating walls 17. This not only chills

the arc and causes the evolution of the deionizing gasses but also, due to the shape of the parts, provides a slot-like small arcuate shaped passage in which the arc is confined. This passage widens downwardly and outwardly and presents a narrowed portion towards the metal parts of the circuit breaker. Consequently, the arc is directed outwardly away from the other portions of the circuit breaker and is quickly extinguished and also its volume or cross-sectional area is maintained at a relatively small value even under heavy overload conditions.

It is to be noted that auxiliary walls or inner walls 21 are provided and that these inner walls 21 constitute with the outer walls 17 baffles between which all portions of the arc are confined. It is understood in this discussion that there is, of course, an arc formed on each side of the circuit breaker and that the action on each arc is identically the same. It is to be noted further that the inner plates 21 of insulating material are spaced from the inner walls 14 and it is understood that both the inner plates 21 and the outer plates 17 are flexible and that these is, therefore, a yield under gas pressure. This yield, though slight, is sufficient to prevent shock stresses of dangerous values from being imposed on the parts of the circuit breaker and, therefore, prevent shattering.

It will be seen that a novel circuit breaker has been provided which will limit the expansion of the arc, which will confine it to a restricted zone, which does not produce excessive stresses on the parts of the circuit breaker and which directs the arc outwardly. Further it is to be noted that this invention provides means for presenting extended cooling surfaces of insulating material to the arc so as to quickly chill the arc and as pointed out above, allow the formation of deionizing gases to thus further assist in the quick suppression of the arc.

It is to be understood that the contacts of the circuit breaker are intended to operate submerged in oil in accordance with the usual practice.

Although this invention has been described in considerable detail it is to be understood that such description is intended as illustrative rather than limiting, as the invention may be variously embodied and is to be interpreted as claimed.

I claim:

1. In a circuit breaker adapted to open under overload comprising a U-shaped insulating body portion, a pair of rocking switch arms located on the outer side of said U-shaped insulating body portion and pivoted adjacent their lower ends and having movable contacts carried adjacent their outer ends, a connecting bar electrically connecting and mechanically joining said movable contacts and constituting with said switch arms and movable contacts a movable contact assembly, means for moving said movable contact assembly into and out of switch closed position, a pair of stationary contacts located on the outer side of said U-shaped body portion and arranged to be engaged and disengaged by said movable contacts, an inner and an outer insulating plate located in pairs on opposite sides of said U-shaped body portion and partially housing said contacts, and a stationary arcuate insulating barrier located inside of the path of travel of each of said movable contacts in contact with the corresponding inner insulating plate and spaced from the corresponding outer insulating plate to provide a slot for each of said

movable contacts, said circuit breaker having pockets for the stationary contacts and said outer plates having vent holes opening into said pockets.

2. In a circuit breaker adapted to open under overload comprising a U-shaped insulating body portion, a pair of rocking switch arms located on the outer side of said U-shaped insulating body portion and pivoted adjacent their lower ends and having movable contacts carried adjacent their outer ends, a connecting bar electrically connecting and mechanically joining said movable contacts and constituting with said switch arms and movable contacts a movable contact assembly, means for moving said movable contact assembly into and out of switch closed position, a pair of stationary contacts located on the outer side of said U-shaped body portion and arranged to be engaged and disengaged by said movable contacts, an inner and an outer insulating plate located in pairs on opposite sides of

said U-shaped body portion and partially housing said contacts, and an arcuate insulating barrier located inside of the path of travel of said movable contacts in contact with the corresponding inner insulating plate and spaced from the corresponding outer insulating plate to provide a slot for each of said movable contacts, said inner and outer plates being yielding and arranged to yield under gas pressure incident to the formation of an arc.

10 15 20 ANTHONY VAN RYAN.
